UNITED STATES PATENT OFFICE.

WILLIAM C. ANDERSON, OF CHICAGO, ILLINOIS, ASSIGNOR TO THE LIBBEY GLASS COMPANY, OF TOLEDO, OHIO, A CORPORATION OF OHIO.

DESIGN FOR A CUT-GLASS VESSEL.

SPECIFICATION forming part of Design No. 36,275, dated April 7, 1903.

Application filed February 18, 1903. Serial No. 144,005. Term of patent 7 years.

To all whom it may concern:

Be it known that I, WILLIAM C. ANDERSON, a citizen of the United States, residing at Chicago, in the county of Cook and State of Illinois, have invented and produced a new, original, and ornamental Design for a Cut-Glass Vessel, of which the following is a specification, reference being had therein to the accompanying drawings, in which—

Figure 1 is a perspective view of the inverted vessel; and Fig. 2 is a section on line *x x*, Fig. 1.

The outer surface is ornamented by a series of substantially circular cuttings A, the circles intersecting at the center *a* of the design and extending into adjacency to the periphery. These circles also intersect at points *b* substantially midway between center and periphery, so as to form intermediate the intersecting circles a series of pointed ornaments B, radiating from the center *a*.

The portion of the circles intermediate the points of intersection *b* and adjacent to the periphery form, in conjunction with complementary arcs C, similar pointed ornaments D, radiating from the center *b*. Intermediate the ornaments B and D are formed the rosettes E, consisting each of an inner raised

circular portion *c* and a surrounding section ornamented by cuttings substantially tangential to the inner circle. The ornamental points B and D consist each of arc-shaped cuttings *e* and *f*, intersecting at the same points with the curved and beaded ribs *g* and central pointed ribs *h*, ornamented by cross-cuttings *h'*.

Fan-shaped ornaments F appear intermediate the points D and the periphery of the article, the latter having an escalloped edge *i*.

The leading feature of the design consists in the appearance produced by the intersecting circles and arcs forming ornamental points radiating from the center of the design and a plurality of points between said center and the periphery, together with the rosettes and the spaces intermediate said points.

What I claim as my invention is—

The ornamental design for a cut-glass vessel substantially as described.

In testimony whereof I affix my signature in presence of two witnesses.

WILLIAM C. ANDERSON.

Witnesses:

JOHN FODEY,
GEO. TALAFOUS.
